UNITED STATES PATENT OFFICE

PAUL F. COX, OF CHICAGO, ILLINOIS, ASSIGNOR TO THE GOSS PRINTING PRESS COMPANY, OF CHICAGO, ILLINOIS, A CORPORATION OF ILLINOIS

MULTICOLOR FLAT-BED WEB-PRINTING PRESS

Application filed January 28, 1929. Serial No. 335,658.

This invention is a novel improvement in flat bed web printing presses of the type shown for example in my Patent 1,475,566 of November 27, 1923 and which is known to the trade as the "Comet" press; but the invention is applicable to other flat bed web perfecting presses and might be used in connection with rotary web printing presses.

The principal object of the invention is to provide novel means whereby a web (or webs each) of one half the width (or less) of the press after being printed upon by the lower bed can be turned between the beds so it will receive a second impression in color on the same side of the web on the top bed, the web returning directly over its lower path of travel and on the same side of the press. By this means I am able to print in colors on one side of the web, by running two narrow width rolls of paper, or slitting a full width web.

A further object of the invention is to provide such a press with two folding mechanisms and means for directing two narrow webs or two longitudinal sections of a web to separate folders, or to the same folder.

In the preferred form of the invention I employ sets of angle bars for turning the webs between the first and second beds or printing mechanisms, such angle bars when applied to a flat bed press being located at the rear end of the press, and the folding or delivery mechanisms being located at the drive end of the press and preferably on opposite sides thereof. With such angle bars and two deliveries I can utilize up to the full printing capacity of the press to print a full width web or its equivalent for bill work. Also to deliver two single page bills in colors, or one in two colors and one in black.

By employing the angle bars and two folders one on each side of the press as stated I can double the product which would be ordinarily obtainable from the press in so-called "bill printing".

My invention also enables the press to simultaneously print up to a six-page newspaper, and a bill from one seventy-inch roll of paper at the same time; and with the rear

end angle bar attachment the bill could be in color.

I will explain the invention with reference to the accompanying drawings which illustrate diagrammatically a flat bed web printing press, equipped with web-turning and web delivering devices in accordance with my invention; and an understanding thereof will enable others skilled in the art to adopt and use the invention. In the claims I have summarized the essentials of the invention and the novel features of construction and novel combinations of parts for all of which protection is desired.

In the drawings:

Figure 1 is a diagrammatic side elevation of a flat bed web printing press equipped with web turning devices and web folding devices in accordance with my invention.

Figure 2 is a diagrammatic top plan view showing the arrangement of web turning and folding devices.

Figure 3 is a rear end view of the web turning devices.

In the drawings 1 and 1^a designate parallel type beds arranged one over the other. Cooperating with bed 1 is an impression cylinder 2, and cooperating with bed 1^a is an impression cylinder 2^a. These cylinders are mounted in bearings in crossheads 3 which are reciprocated to move the cylinders 2 and 2^a back and forth over the beds, preferably by means of pitmen 3^a connecting the crossheads 3 with crank gears 4. The press is provided with web feeding, guiding and delivery mechanism. The press shown is of the type illustrated in my Patent 1,475,566 and is fully described therein and the general construction and arrangement of such machine and of the aforesaid parts are well known and need no further detailed explanation herein, but as stated the invention is applicable to other types of presses.

In the press shown when it is desired to print an ordinary newspaper, or perfect both sides of a web, the web *w* is led from the roll *W* under an idler guide roller *g* to an infeed roll 5, then the web is led under a guide roller *g'* to a guide roller *g*², and then back over a looping roller 6^a. The web is then led over

the bed 1^a and under the cylinder 2^a to and over a guide roller g^3 mounted on the crossheads adjacent cylinder 2^a , and up over a guide g^4 mounted on the crossheads beside cylinder 2^a ; the web then passes to a stationary guide g^5 on the frame; and up over a roller g^6 on the frame; thence inwardly over bed 1 to a guide g^7 on the crossheads adjacent cylinder 2 ; then under cylinder 2 and up over a guide g^8 mounted on the crossheads beside cylinder 2 ; then forward to and around a looping roller 6^b thence back under a guide g^9 ; thence to and over a tension roller 7 ; to the delivery roll 8 . From roll 8 the web w passes to the folding and delivering devices.

As above stated the present invention provides means for enabling such a press to print a web on one side in multicolor if desired; or to print two narrow webs, or two sections of a wide web, in multicolor if desired; to print one narrow web or web section in multicolor on one side and perfect the other narrow web or web section in one color; and to provide means whereby such narrow webs or web sections can be delivered either together, or separately.

In order to enable the press to print a narrow web or two sections of a web in multicolor on one side, I provide two sets of web turning devices intermediate the upper and lower beds and cylinders and preferably located adjacent the rollers g^6 and g^5 . Each set of web turning devices comprises upper and lower angle bars 10 and 10^a , and intermediate guide rollers 10^b and 10^c , which are at right angles to the guides g^5 and g^6 . These web turning devices are properly supported in suitable framing not shown, which can be readily supplied by the press designer, and one set with turning devices is conveniently located above the other set of web turning devices to facilitate threading the webs therethrough.

When it is desired to print the web on one side in multicolor two narrow webs may be used, or the narrow webs may be sections of the wide web w .

As indicated the wide web w may be split either before being printed on the first bed by means of an ordinary slitter, indicated at S , in Fig. 1; or the wide web may be slit after being printed on bed 1^a , as by a slitter indicated at S' in Fig. 1. The slitter can be located at any convenient point to divide the web into two sections w' and w^2 .

The web w' after passing the roller g^5 is turned over the angle bar 10 , and led out to and over the guide 10^a ; then back to and over the guide 10^b , and then to and over the angle bar 10^c , by which it is directed back to and under roller 10^d , and thence up to the roller g^6 from which it passes on through the machine as above described and receives a second impression in color on the same side from

the form on bed 1 . The web w^2 after passing the roller g^5 is led up over a guide 10^e to and over the angle bar 10^x then to and over the guide 10^{ax} , then to the roller 10^{bx} , then to and over the angle bar 10^{cx} , and thence to the roller g^7 , from which it passes on to receive the second impression in color on the same side from the form on bed 1 as above described.

The two sections w' and w^2 of the web after passing the roller 8 , may be directed to either folder F or F' , which are preferably arranged at opposite sides of the machine as indicated in Fig. 2. If it is desired to deliver both sections w' and w^2 to the folder F the webs w' and w^2 are turned over angle bars 11 , at the drive end of the press, and led direct to the folder F in the usual manner. If desired to deliver both webs w' and w^2 to the folder F' , both said webs can be turned over angle bars 11^a and led direct to the folder F' . If it is desired to deliver the webs w' and w^2 separately; web w' can be turned over angle bar 11 and sent to folder F , and web w^2 can be turned over angle bar 11^a and sent to former F' . As the manner of mounting and supporting angle bars and folders and the general construction of arrangement of folders are well known it is not necessary to illustrate all these parts in detail.

It will be seen from the foregoing that in a press provided with the described web turning attachments two narrow webs or sections of a wide web can be turned over between the first and second printing couples and be printed simultaneously in two colors on the same side.

By providing the press with two folders or delivery devices and suitable related angle bars as described, the product from each half of the press can be led to a single folder or to separate folders.

A press equipped with my invention can deliver simultaneously two perfected products; or two multicolor products, or a multicolor product and a perfected product; and these products can be varied in size.

The total product of the press can be delivered to either folder; or it is possible to deliver a product up to $\frac{3}{4}$ of the width of the press to either folder, and the product from the remaining $\frac{1}{4}$ of the width of the press to the other folder.

I claim:

1. In a web printing press; two printing couples, each comprising a flat bed and a co-acting traveling cylinder, and means for feeding a wide web or two narrow webs or sections of webs through the press whereby they may be perfected if desired; of means intermediate the printing couples for turning the narrow webs or sections of web after they have been printed by the first couple so that the same side of such narrow webs will be printed by the second printing couple.

2. In combination with printing mechanism as set forth in claim 1 means for delivering the printed webs or sections either separately or together.
- 5 3. In a printing press as set forth in claim 1 a plurality of folders, and means whereby the narrow webs or web sections may be directed to the same folder, or to different folders, and delivered either separately or together.
- 10 4. In a web printing press; two flat bed-and-cylinder printing couples arranged one over the other, and means for feeding a wide web or two narrow webs or sections of web through the press whereby they may be perfected if desired; of means adjacent one end of the press for turning the narrow webs or sections of web after they have been printed by the first couple so that the same sides of such webs will be printed by the second printing couple.
- 15 5. In combination with printing mechanism as set forth in claim 4 means for delivering the printed webs either separately or together.
- 20 6. In a printing press as set forth in claim 4, a pair of folders, and angle bars whereby the printed web or web section may be directed to either folder, and delivered either separately or together.
- 25 7. In a web printing press; two bed-and-cylinder printing couples arranged one above the other; and means for feeding a wide web or two narrow webs or sections of web through the press whereby they may be perfected if desired; sets of angle bars and web guides at one end of the press and between the first and second printing couples, for turning the narrow webs or sections of web after they have been printed by the first couple so that the same sides of such webs may be printed in color by the second printing couple.
- 30 8. In combination with printing mechanism as set forth in claim 7 means for folding the printed webs either separately or together.
- 35 9. In a printing press as set forth in claim 7, a pair of folders adjacent the feed end of the press and angle bars whereby the webs printed by the press may be directed to either folder, and be folded and delivered either separately or together.
- 40 10. In a web printing press, two bed-and-cylinder printing couples and means for feeding a wide web or two narrow webs or sections of web through the press; of two sets of devices adjacent one end of the press for turning a narrow web or section of a wide web after it has been printed by the first couple so that the same side of such web will be printed in color by the second printing couple.
- 45 11. In combination with printing mechanism as set forth in claim 10, means for delivering the printed webs either separately or together.
- 50 12. In a printing press as set forth in claim 10, a pair of folders and angle bars whereby either section of the printed web may be directed to either folder, and the webs be folded and delivered either separately or together.
- 55 13. In a web printing press; bed and cylinder printing couples arranged one above the other; means for feeding a wide web or two narrow webs or sections of web through the press; two sets of angle bars and web guides at one end of the press and between the first and second printing couples for turning narrow webs or sections of web after they have been printed by the first couple so that the same sides of such webs may be again printed in color by the second printing couple.
- 60 14. In combination with printing mechanism as set forth in claim 13, means for folding the printed webs either separately or together.
- 65 15. In a printing press as set forth in claim 13, a pair of folders at opposite sides of the press and adjacent the feed end thereof, and angle bars whereby the webs printed by the press may be directed to either folder and be folded and delivered either separately or together.
